UNITED STATES PATENT OFFICE.

KARL ARPAD BARENYI, OF BERLIN-LICHTERFELDE, GERMANY.

ELECTRIC STARTER FOR INTERNAL-COMBUSTION ENGINES.

Application filed May 12, 1924. Serial No. 712,914.

To all whom it may concern:

Be it known that I, KARL ARPAD BARENYI, a citizen of Germany, residing at Berlin-Lichterfelde, in the State of Prussia, Germany, have invented certain new and useful improvements in Electric Starters for Internal-Combustion Engines; and I do hereby declare the following to be a full, clear, and exact description of the invention, such as will enable others skilled in the art to which it appertains to make and use the same.

My invention relates to improvements in electric starters for internal combustion engines and the power transmission gearing provided in the said starter, and the object of the improvements is to provide a gearing which is compact in construction, which has a high gear ratio, which comprises a small number of gear wheels, and which has a high efficiency. With this object in view I provide a pair or pairs of coaxial intermediate bevel gears of different diameters mounted on a common axis disposed angularly of the driving and driven shafts, the bevel gear wheel of larger diameter meshing with a bevel gear of small diameter mounted on one of said shafts and the bevel gear wheel of smaller diameter meshing with a bevel gear wheel of large diameter mounted on the other shaft, and the intermediate gear wheel of larger diameter being located between the axis of the driving and driven shafts and the intermediate gear wheel of smaller diameter.

My improved power transmission gearing may be used in many cases where a high gear ratio, a small number of gear wheels and high efficiency are desired and where the whole structure must be provided within a small space. An important field of application of the gearing are electric starters for internal combustion engines. As is known, in electric starters provided on motor vehicles and constructed for starting the engine, charging a storage battery and supplying energy to the electric lighting system and the igniting apparatus, there is ordinarily little room for disposing the starter. Therefore the dimensions of the starting system must be reduced as far as possible. On the other hand a high torque must be developed for starting and the ef-

ficiency of the gearing connecting the starter and the engine must be high. These conditions are satisfied by my improved gearing.

For the purpose of explaining the invention I shall describe the same as embodied in an electric starter for internal combustion engines. But I wish it to be understood that my invention is not limited to the use of the gearing in connection with an electric starter. In the drawings,

Fig. 1, is a longitudinal horizontal section of the electric starter and the gearing connected therewith,

Fig. 2, is a cross-section taken on the line 2—2 of Fig. 1 and looking in the direction of the arrows, and

Fig. 3, is a diagrammatical elevation showing the starter and an internal combustion engine.

The general construction of the starting system is known in the art and it has been described in detail in the patent of the United States No. 1,487,193 granted to me March 18, 1924. Therefore I deem it not necessary to describe the electrical part of the system in detail, a general reference to the main parts being sufficient to give a clear understanding of the electric apparatus.

In the example shown in the drawings the electric part of the system and the transmission gearing are mounted in a cylindrical casing 1 having field poles 2 secured thereto. The armature 3 and its commutator 4 are secured to a shaft 5 mounted near its end in an anti-friction bearing 13 disposed within the cylindrical portion 14 of a member 14, 25, 26. The portion 14 is mounted in an anti-friction bearing 15 disposed within a ring 27 secured to the casing 1. Coaxially of the shaft 5 a shaft 6 is mounted in an anti-friction bearing 23, and is made integral or connected with the crank shaft of an internal combustion engine 28. The shaft 6 is formed with an axial bore having a bushing 29 fitted therein and providing a bearing for the reduced end 5' of the shaft 5. To the end of the shaft 5 a bevel gear or pinion 7 is secured, and to a flange 30 of the adjacent end of the shaft 6 a bevel gear 8 the teeth of which are disposed substantially in

the same transverse plane as the teeth of the pinion 7.

Between the flange 30 and the cylinder 26 there is an anti-friction bearing 16 providing a second support for the member 14, 25, 26. To the said member inclined shafts 12 are secured which are provided with bushings 31 having tubular members 11 rotatably mounted thereon, which members are made integral each with a bevel gear 9 and a bevel gear or pinion 10, the bevel gear 9 meshing with the pinion 7, and the pinion 10 with the bevel gear 8. The cylindrical portion 26 is formed with circumferential ratchet teeth 17 adapted to be engaged by a pawl 18 mounted in a cap 19 secured to the casing 1 and adapted to lock the annular member 14, 25, 26 as against rotation in anti-clockwise direction and permitting rotation in clockwise direction. To the cylindrical portion 14 a ring 32 formed with ratchet teeth is secured which cooperates with a ring 33 formed with corresponding ratchet teeth and longitudinally slidable but non-rotatable on the shaft 5. The ratchet teeth on the said rings are constructed so that rotary movement of the shaft 5 in clockwise direction is not transmitted therethrough to the member 14, 25, 26, while clockwise rotary movement of the member 14, 25, 26 is transmitted to the shaft 5. The ring is acted upon by a spring 34 bearing on a ring 35 and tending to force the ratchet teeth of the ring 33 into engagement with the ratchet teeth of the ring 32. The ring 35 is provided with clutch teeth 36 cooperating with clutch teeth 37 formed on the cylindrical portion 14, and it is adapted to be shifted with its teeth into coupling engagement with the teeth 37 by means of a transverse pin 38 connected with a rod disposed within an axial bore of the shaft 5 when starting the engine by hand, as has been described in my aforesaid patent.

To the shaft 6 a spur gear 20 is keyed which is in mesh with a spur gear 21 forming a part of the distributor of the igniting apparatus and interrupter 22 which is therefore directly driven from the shaft 6.

The operation of the apparatus is as follows: For starting the internal combustion engine current is supplied to the armature 3, which acts as a motor and is rotated in clockwise direction. The teeth of the rings 32 and 33 are constructed so that they do not couple the shaft 5 with the cylindrical portion 14. The rotary movement of the shaft 5 is transmitted by the pinion 7 to the gears 9 and 10. By reason of the reaction of the engine such rotary movement of the gear 10 tends to cause planetary movement of the gears 9, 10 and the annular member 14, 25, 26 in anti-clockwise direction, which planetary movement is prevented by the pawl 18 permitting only clockwise rotation of the said annular member. Therefore the pin-

ions 10 impart rotary movement to the bevel gearing 8, the shaft 6 and the crank shaft of the engine. By the gears 7, 9 and 10, 8 the speed of the shaft 6 is reduced as compared to that of the armature. After the engine 70 has become self-operating it builds up speed so that finally the circumferential velocity of the gear 8 tends to exceed that imparted by the armature 3 to the pinion 10. However, by reason of the resistance of the armature 3 such increased velocity is not transmitted to the shaft 5, but the gear 8 carries around the pinions 10 which therefore perform planetary movement in clockwise direction and carry along the annular member 14, 25, 26 80 which is now coupled by the teeth 32, 33 with the shaft 5, whereupon power is transmitted from the shaft 6 through the annular member 14, 25, 26 to the shaft 5.

For starting the engine by hand the ring 35 is shifted to the left and into engagement with the teeth 37 formed on the member 14 the rotary movement of which is directly transmitted to the flange 30 of the shaft 6.

In the description no reference has been made to the electric connection of the armature because my invention has reference only to the power transmission gearing and its connection with the electric system. The 95 operation of the electrical system has been described in my aforesaid patent.

By constructing the planet gears 9, 10 in the manner described with their axes 12 angularly of the axis of the driving and driven 100 shafts 5 and 6 and with the gear 9 of large diameter meshing with the gear 7 of small diameter and the small gear 10 meshing with the large gear 8 a compact transmission 105 gearing is obtained, because the large gear 9 does not project beyond the circumference of the gear 8. As appears from the drawing the gear 9 may have a large diameter without projecting beyond the circumference of the gear 8, the pinion 10 projects only 110 slightly beyond the said circumference, and the gears 7 and 8 are disposed within the same transverse plane. Thus a gearing of high gear ratio is disposed within a small space. The gear wheels 8 and 10 may be 115 constructed with strong teeth adapted to transmit high power.

It will be understood that my improved power transmission gearing is suitable for use in connection with many systems in 120 which compact structure and high gear ratio are desired. An important field of application are starters for internal combustion engines mounted on motor vehicles. Such systems must be disposed within a very small 125 space. Therefore the dimensions of the apparatus must be reduced to a minimum. On the other hand the electric machine must be able to transmit a large torque to the engine, which means high gear ratio and high effi- 130

ciency. My improved gearing answers to these requirements. When generating electric energy as well as when starting the engine the main pressure is exerted on the 5 teeth of the gears 10 and 8 which can be made very strong. When starting the engine the pressure on the teeth of the gears 7 and 9 is comparatively low, and when generating current no pressure is exerted on the 10 said teeth, the power being transmitted directly through the annular member 14, 25, 26.

While in describing the invention reference has been made to a particular example 15 embodying the same I wish it to be understood that my invention is not limited to the construction shown in the drawings, and that various changes may be made in the general arrangement of the apparatus and 20 the construction of its parts without departing from the invention.

I claim:

1. In a gearing, the combination, with two 25 shafts in axial alinement with each other, of bevel gears of different diameters respectively mounted on said shafts, and coaxial bevel gears of different diameters connected with each other and having their axis disposed angularly of the axis of said shafts, 30 the larger bevel gear of the coaxial gears meshing with the smaller bevel gear on one of said shafts and the smaller bevel gear of the coaxial gears meshing with the larger bevel gear on the other one of said shafts.

35 2. In a gearing, the combination, with two shafts in axial alinement with each other, of bevel gears of different diameters respectively mounted on said shafts substantially within the same transverse plane, and coaxial bevel gears of different diameters connected with each other and having their axis disposed angularly of the axis of said shafts, the larger bevel gear of the coaxial gears meshing with the smaller bevel gear on one 40 of said shafts and the smaller bevel gear of the coaxial gears meshing with the larger bevel gear on the other one of said shafts.

3. In an electric starter for internal combustion engines, the combination, with an 50 electric machine and its shaft, and a shaft for starting an internal combustion engine, of a bevel gear secured to said armature shaft, a bevel gear larger in diameter than said gear on the armature shaft and mounted on said shaft for starting the engine, and a pair of coaxial bevel gears of different diameters mounted on a shaft disposed angularly of said armature and engine shafts, and meshing the gear wheel of smaller diameter with the gear wheel on the engine shaft and the gear wheel of larger diameter with the gear wheel on the armature shaft.

4. In an electric starter for internal combustion engines, the combination, with an 55 electric machine and its shaft, and a shaft for starting an internal combustion engine, of a bevel gear secured to said armature shaft, a bevel gear larger in diameter than said gear on the armature shaft and mounted on said shaft for starting the engine, a

for starting an internal combustion engine, of a bevel gear secured to said armature shaft, a bevel gear larger in diameter than said gear on the armature shaft and mounted on said shaft for starting the engine, the 70 teeth of said gear being disposed substantially in the same transverse plane, and a pair of coaxial bevel gears of different diameters mounted on a shaft disposed angularly of said armature and engine shafts and meshing the gear wheel of smaller diameter with the gear wheel on the engine shaft and the gear wheel of larger diameter with the gear wheel on the armature shaft. 75

5. In an electric starter for internal combustion engines, the combination, with an electric machine and its shaft, and a shaft for starting an internal combustion engine, of a bevel gear secured to said armature shaft, a bevel gear larger in diameter than 80 said gear on the armature shaft and mounted on said shaft for starting the engine, a pair of coaxial bevel gears of different diameters mounted on a shaft disposed angularly of said armature and engine shafts 85 and meshing the gear wheel of smaller diameter with the gear wheel on the engine shaft and the gear wheel of larger diameter with the gear wheel on the armature shaft, a member having said coaxial gears mounted thereon and rotatable coaxially of said armature and engine shafts, and means to lock said member as against rotation in one direction. 90

6. In an electric starter for internal combustion engines, the combination, with an electric machine and its shaft, and a shaft for starting an internal combustion engine, of a bevel gear secured to said armature shaft, a bevel gear larger in diameter than 100 said gear on the armature shaft and mounted on said shaft for starting the engine, a pair of coaxial bevel gears of different diameters mounted on a shaft disposed angularly of said armature and engine shafts 105 and meshing the gear wheel of smaller diameter with the gear wheel on the engine shaft and the gear wheel of larger diameter with the gear wheel on the armature shaft, a member having said coaxial gears mounted thereon and rotatable coaxially of said armature and engine shafts, and means to lock said member as against rotation in one direction, 110 and a clutch operative in one direction only for coupling said member with the armature shaft for transmitting power thereto. 115

7. In an electric starter for internal combustion engines, the combination, with an electric machine and its shaft, and a shaft for starting an internal combustion engine, of a bevel gear secured to said armature shaft, a bevel gear larger in diameter than 120 said gear on the armature shaft and mounted on said shaft for starting the engine, a

pair of coaxial bevel gears of different diameters mounted on a shaft disposed angularly of said armature and engine shafts, and meshing the gear wheel of smaller diameter with the gear wheel on the engine shaft and the gear wheel of larger diameter with the gear wheel on the armature shaft,

a distributor and interrupter and a gear connected therewith, and a gear on said engine shaft meshing with said gear of the distributor and interrupter.

In testimony whereof I hereunto affix my signature.

K. ARPAD BARENYI.
